DESIGN FOR A DRAFTSMAN'S ERASER

Benjamin W. Hanle, Elizabeth, N. J., assignor to Eagle Pencil Company, New York, N. Y., a corporation of Delaware

Application June 21, 1941, Serial No. 101,609

Term of patent 14 years

To all whom it may concern:

Be it known that I, Benjamin W. Hanle, a citizen of the United States and residing at Elizabeth, in the county of Union and State of New Jersey, have invented a new, original, and ornamental Design for Draftsman's Eraser, of which the following is a specification, reference being had to the accompanying drawing, forming part thereof and in which

Fig. 1 is a perspective view of the eraser supported on one of its broad sides,

Fig. 2 is a side elevation thereof and supported on one of its broad sides,

Fig. 3 is a perspective view of the eraser when supported on one of its narrow sides and

Fig. 4 is an end elevation thereof.

I claim:

The ornamental design for a draftsman's eraser, substantially as shown.
